TYPEWRITER DESK

John H. White, High Point, N. C.

Application April 19, 1940, Serial No. 330,624

12 Claims. (Cl. 312—24)

My invention relates to improvements in typewriter desks.

An important object of the invention is to provide a flat top typewriter desk, having ample knee space when the desk is opened and closed whereby the same is highly convenient in use.

A further object of the invention is to provide means for connecting and operating the typewriter table and the cover, in unison and locking the typewriter table in the raised position against improper downward movement.

A further object of the invention is to provide a desk of the above mentioned character which is of simplified construction and which may be manufactured comparatively cheaply and which is easy to operate.

Other objects and advantages of the invention will be apparent during the course of the following description.

In the accompanying drawing forming a part of this application and in which like numerals are employed to designate like parts throughout the same,

Figure 1 is a perspective view of the typewriter desk embodying my invention, showing the same open,

Figure 2 is a central transverse vertical section through Figure 1, showing the desk opened,

Figure 3 is a similar view showing the desk closed,

Figure 4 is a perspective view of the cover sections and associated elements,

Figure 5 is a plan view of a stationary table and movable table and associated guides,

Figure 6 is a longitudinal section taken on line 6—6 of Figure 5, showing the typewriter in place, and,

Figure 7 is a transverse section taken on line 7—7 of Figure 5.

In the drawing, wherein for the purpose of illustration is shown a preferred embodiment of my invention, the numeral 5 designates a flat top typewriter desk as a whole, having two sets of drawers 6. The desk further comprises a flat top 7 and the desk has a well 8, and an opening 9 is formed in the top 7 and leads into the well. The well has side walls 10, included in the cabinets which hold the drawers 6. The foregoing description is that of the conventional flat top typewriter desk. The present invention may be applied to a flat top typewriter desk having two sets of drawers 6 or a single set and the invention is not restricted to its application to the precise form of desk shown.

The numeral 11 designates a front stationary

table, which is horizontal, and arranged within the upper portion of the well 8 at the front of the well, and preferably projects slightly to the exterior of the well. This stationary table is suitably secured to the side walls 10 and associated parts of the desk, preferably in a manner to deaden the sound produced by the operation of the typewriter. The stationary table 11 is arranged at a sufficiently high elevation to provide ample knee space when the desk is being used. The stationary table 11 is arranged at an elevation beneath and spaced from the flat top 7. Disposed at the rear of the stationary table 11 is a swinging typewriter table 12, hinged to the stationary table 11, as shown at 13. The hinges 13 are arranged upon the lower faces of the tables 11 and 12 and provide a knee joint which breaks downwardly. The swinging table 12 may be moved upwardly to a horizontal position flush with the stationary table 11, Figure 2, or lowered to an inclined position, Figure 3. The table 12 is arranged within the well 8 and has a back 14 rigidly attached to the table 12, which back serves to prevent the displacement of a typewriter 15, as shown. When the swinging table 12 is in the lowermost position it engages a stationary vertical partition or board 16 suitably secured to the side walls 10, as shown.

The opening 9 is closed by a cover including a forward cover section 17 and a rear cover section 18, which operate within the opening 9 and well 8 and are flush with the upper surface of the flat top 7 when the cover sections are in the raised positions. The adjacent edges of the cover sections 17 and 18 are connected by hinges 19, arranged upon the lower faces thereof, and forming a knee joint which breaks downwardly. The forward cover section 17 has a rail 20 secured thereto, adjacent to its forward edge, and this rail is arranged beneath the cover section 17 and is adapted to engage the stationary table 11, when the cover sections 17 and 18 are in the closed position, thus serving to limit the downward movement of the forward edge of the cover section 17.

Disposed adjacent to each end of the cover section 17 and beneath the cover section is a link 21, one end of which is pivotally mounted upon the wall 10 by means of a fixed pivot 22. The opposite end of the link 21 is pivotally connected at 23 with a bracket 24, rigidly secured to the cover section 17 near and spaced from its forward edge. The pivot 22 is arranged near and spaced from the rear edge of the cover section 17 when this cover section is in the raised

position, as shown in Figure 3. The links 21 cause the cover section 17 to swing in a curved path when the same is raised and lowered.

Rigidly attached to each wall 10 by means of screws 25 or the like is a stationary bracket 26. This stationary bracket has a lever 27 pivotally mounted thereon between its ends, as shown at 28. The lever 27 has a long arm which is pivotally connected, at 29, with a bracket 30, and this bracket is arranged beneath and rigidly secured to the rear cover section 18, adjacent one end thereof and preferably spaced from its forward and rear edges, as shown. The lever 27 is pivotally connected at 31 with a link 32, and this link is pivotally connected at 33 with an arm-bracket 34. This arm-bracket is disposed adjacent to one end of the swinging table 12, is rigidly secured thereto and is disposed perpendicular to the surface of the table and projects above the same for a substantial distance, as shown. The lever 27 and link 32 and associated elements serve to connect the rear cover section 18 with the table 12 so that the movement of the cover section 18 is transmitted to the table 12.

Arranged adjacent to each end of the cover section 18 is a link 35, the lower end of which is pivotally connected with the bracket 26 as shown at 36 and its upper end is pivotally connected, as shown as 37, with the bracket 30. When the cover section 18 is in the raised position, Figure 3, the link 35 crosses the lever 27. The link 35 causes the cover section 18 to swing in a curved path when being raised and lowered and when the cover section 18 is in the lowermost position, it engages the vertical partition or stop 16.

The stationary table 11 has a substantial width so that the swinging table 12 will occupy a suitable rearward position when lowered, thereby affording ample knee space when the cover sections 17 and 18 are closed and the desk is being used as a flat top desk. Since the table 12 occupies a rearward position, the available space for the downward movement of the cover is reduced, and hence the cover is rendered foldable by forming the same in the hinged sections 17 and 18. It is, of course, understood that the links 21, 32 and 35 and the levers 27 are thin, and that there is sufficient space at the ends of the table 12 and cover section 17 for the passage of these links. This space is present in the conventional folding typewriter desk and is shown, for instance, in Figure 3 of Patent 675,729.

The operation of the desk is as follows:

With the cover sections 17 and 18 in the closed position, Figure 3, the desk is opened by the operator raising the cover section 17 and swinging it rearwardly and downwardly until it assumes the position shown in Figure 2. The links 21 cause the cover section 17 to swing in a curved path, and the links 35 cause the cover section 18 to swing in a curved path. When the cover section 18 moves downwardly, Figure 2, it swings the lever 27 upon the pivot 28 and the short arm of the lever moves the link 32 upwardly and this link acts upon the arm-bracket 34, shifting the arm-bracket to the raised vertical position. The arm-bracket swings the table 12 upwardly to the horizontal position so that its upper surface is flush with the upper surface of the stationary table 11. When the table 12 is thus raised to the horizontal position, the pivot 31 of the link 32 is moved slightly rearwardly past dead center and hence the link 32 is locked at substantially a straight angle with relation to

the lever 27. The lower end of the lever 27 cannot now swing forwardly because the cover section 18 engages the stationary partition 16. It is thus seen that the table 12 is locked against downward movement due to downward pressure exerted thereon. When the table 12 was in the lowered position the typewriter 15 engaged the back 14, and the typewriter is now shifted forwardly upon the stationary table 11, Figure 2. To close the desk, the typewriter 15 is slid back upon the table 12 so that it contacts with the back 14, and the cover section 17 is now moved forwardly and the reverse operation of the parts occurs and these parts then assume the position shown in Figure 3. In practice, I have found it satisfactory to have the stationary table 11 ten inches wide as this will afford a suitable support for the average typewriter and the table 12 is sufficiently wide to receive the typewriter. Of course the invention is not restricted to these dimensions. The table 11 serves as a support for the hinges 13 of the table 12 whereby these hinges 13 are located at a considerable rear distance from the front of the desk. While it is preferred to use the stationary table 11, yet this table might be dispensed with and a narrow support used for the hinges 13, at the location shown. If this were done, the typewriter would remain upon the table 12 when the table 12 is raised and the operator would move in further toward the typewriter.

In Figures 5 to 7 inclusive, I have shown guide means for the typewriter 15. The stationary table 11 is provided with transverse grooves 38 which are transversely tapered and increase in width upwardly. These transverse grooves 38 are in alignment with transverse grooves 39, which are identical with the grooves 38 and formed in the swinging table 12. The numeral 40 designates guides which are slideable in the grooves 39 and 38 and are transversely tapered and increase in width upwardly. These guides are secured to rubber feet 41 of the typewriter by screws 42 and the guides have lower recesses 43 which receive the heads of the screws. It is obvious that the grooves and guides properly guide the typewriter 15 in its movement toward and from the stationary table 11 and also permit of the ready removal of the typewriter from the tables 11 and 12, when desired. The forward movement of the guides 40 are limited by a fixed rail or flange 44.

While it is preferred to use the guide means for the typewriter, yet the invention is in no sense restricted to such use.

It is to be understood that the form of my invention herewith shown and described is to be taken as a preferred example of the same and that various changes in the shape, size and arrangement of parts may be resorted to without departing from the spirit of my invention or the scope of the subjoined claims.

Having thus described my invention, what I claim is:

- 65 1. A desk comprising a top having an opening and a well, forward and rear cover sections hinged together and movable with relation to the desk, a link means pivotally connected with the cover sections and desk, to guide the cover sections when moved in one direction into the well, a swinging table within the well for movement about a fixed pivot, a lever pivotally mounted between its ends upon the desk, means connecting one end of the lever with one cover section,

and means connecting the other end of the lever with the swinging table.

2. A desk comprising a top and having an opening and a well, forward and rear cover sections hinged together and movable with relation to the desk, a link means pivotally connected with the cover sections and desk, to guide the cover sections when moved in one direction into the well, a swinging table to operate within the well, a fixed pivot means for supporting the table, a lever pivotally mounted upon the desk, means connecting the lever with the swinging table, and means connecting the lever with one cover section.

3. A desk comprising a top and having an opening and a well, a swinging table mounted within the well, means for pivotally supporting the table and permanently retaining the forward edge of the table spaced rearwardly from the front of the desk, a cover for the opening including cover sections which are hinged together, pivot means connected with the desk and cover sections and serving to guide the cover sections into the well when the cover sections are swung rearwardly, and a lever pivotally connected with the desk and one cover section and the table.

4. A desk comprising a top having an opening, said desk having a well, a typewriter table arranged within the well, means to pivotally support the table so that it may be shifted to a raised generally horizontal position and a lowered position, a cover for the opening including cover sections which are hinged together, means to guide the cover sections when moved from the raised position to a lowered position within the well, and connecting means between one cover section and the table so that the table is moved by such cover section.

5. A desk comprising a top having an opening, said desk having a well, a stationary table arranged within the well adjacent to the front of the desk and beneath and spaced from the top of the desk, a swinging table pivotally supported so that it may be swung to an upper generally horizontal position substantially flush with the stationary table and to a lowered inclined position, a cover for the opening including cover sections which are hinged together, means to guide the cover sections so that they may be lowered into the well, and operating connecting means between one cover section and the swinging table so that the table is moved by such cover section.

6. A desk comprising a top having an opening, said desk having a well, a table arranged within the well adjacent to the front thereof and disposed beneath the top, said table having a substantial width, a swinging table within the well at the rear of the first table and adapted to be shifted upwardly to a generally horizontal position and to be lowered to an inclined position, means for supporting the swinging table and serving to retain the forward edge of the swinging table at the rear of the first table, a cover including cover sections which are hinged together, guide means for the cover sections so that they may be lowered into the well, and means operated by one cover section when it is lowered to raise the swinging table.

7. A desk comprising a top having an opening, said desk having a well, a cover for the opening, means to guide the cover into the well, a swinging table arranged within the well, a lever pivoted to the desk and connected with the cover, a link pivotally connecting the lever and table, the

arrangement being such that the link is disposed at substantially a straight angle to the lever when the lever is shifted to a position to move the table to the uppermost position.

8. A desk comprising a top having an opening, said desk having a well, a cover for the opening and movable into the well, a link pivotally connected with the desk and the cover to guide the same in its movement, a swinging table arranged within the well, a lever pivotally connected with the desk and the cover, a link pivotally connected with the lever and pivotally connected with the table, the arrangement being such that the lever and link swings the table to the uppermost position when the cover is in the lowermost position, the link being then disposed at substantially a straight angle to the lever and the pivot connecting the lever and link being slightly rearward past dead center with respect to the pivot which supports the lever so that the table is locked against downward movement.

9. A desk comprising a top having an opening, said desk having a well, a forward table section arranged within the well, and having a substantial width, a rear table section, means for pivotally supporting the rear table section so that it may assume a lowered inclined position with its forward edge adjacent to the rear edge of the forward table section and its rear edge spaced rearwardly from its forward edge, the two table sections providing sufficient knee space, the rear table section being also adapted to be swung upwardly to a generally horizontal position at the rear of the forward table section, a cover for the opening, including cover sections which are hinged together, and means to guide the cover sections so that they may be shifted to a raised position to cover the opening and to a lowered position within the well about the movable table.

10. A desk comprising a top having an opening, said desk having a well, a stationary table section arranged within the well and disposed adjacent to the front of the desk, a movable table section arranged within the well at the rear of the stationary table section, pivot means arranged adjacent to the rear edge of the stationary table section and connected with the movable table section adjacent to the front edge of the movable table section, the arrangement being such that the movable table section may be swung to a lowered position inclining rearwardly from its upper edge toward its lower edge, the movable table section being adapted to be shifted to a generally horizontal position at the rear of the stationary table section, a cover including cover sections which are hinged together, and means to guide the cover sections so that they may be shifted to an upper position to cover the opening and to a lowered position within the well.

11. A desk comprising a top having an opening, said desk having a well, a table section arranged within the well and disposed adjacent to the front of the desk, a movable table section arranged within the well at the rear of the first table section, pivot means arranged adjacent to the rear edge of the first table section and connected with the movable table section adjacent to the front edge of the movable table section, the arrangement being such that the movable table section may be shifted to a generally horizontal position with its forward edge adjacent to the rear edge of the first table section and then shifted to a lowered position with its front edge adjacent to the rear edge of the first table section and the rear edge of the movable table sec-

tion disposed rearwardly of its front edge, a cover for the opening including hinged cover sections, and means to guide the cover sections during their movement to an upper position to cover the opening and a lowered position to enter the well.

12. A desk comprising a top having an opening, said desk having a well, a table section arranged within the well and disposed adjacent to the front of the desk, a second table section arranged within the well and disposed at the rear of the first table section, means to hinge the forward edge portion of the second table

section with the rear edge portion of the first table section, the arrangement being such that the second table section may be shifted to an upper generally horizontal position and to a lowered position inclining rearwardly, a cover including cover sections which are hinged together, and means to guide the cover sections so that they may be shifted to an upper position to cover the opening and to a lowered position to enter the well.
